UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

TRAIN-CONTROL SYSTEM FOR RAILROADS.

Original application filed January 26, 1922, Serial No. 531,903. Divided and this application filed May 16, 1923. Serial No. 639,462.

This invention relates to automatic train control systems for railroads.

In train control systems, it is necessary to transmit or communicate controlling influences or impulses from the trackway to moving vehicles, in order that the train control apparatus on each vehicle may be governed in accordance with the presence or absence of other vehicles, positions of switches, and other conditions affecting the safe progress of the vehicle. On account of weather conditions, problems of clearance, and like difficulties encountered in practice, it is desirable to communicate such controlling influences inductively, that is through an intervening air gap, rather than by a mechanical cooperation or physical contact between devices on the vehicle and devices on the track. With a view of satisfying the principle of failure on the side of safety, so important in railway signaling and train control systems, it is considered preferable to employ an arrangement of car apparatus and trackway devices which will act to produce a stopping influence in case of any failure of circuits or the like; and it is proposed to utilize the magnetic properties of an inert body of iron on the trackway for producing the stopping influence. Since it is desirable to avoid the use of batteries or other source of current on the trackway to put the track device into the inactive or non-stopping condition, it is further proposed to employ a track element structure which is caused to assume its inactive condition by merely closing a circuit without requiring any electrical energy.

With the type of system generally outlined above, it will be evident that the track rails of crossings, switch points, water pans, and similar iron and magnetic bodies along the trackway, will tend to produce an effect upon the car equipment similar to that produced by the regular track elements of the system when in their active stopping condition. Such tendency to produce an unnecessary and false stopping control, conveniently termed rail interference, is of course, highly objectionable in systems of this character; and while various schemes for overcoming this rail interference have been suggested, it is proposed in accordance with the present

invention to select the location and disposition of the cooperating elements on the car and on the trackway in such a way as to 55 practically eliminate such rail interference.

While the general scheme of operation characterizing this invention may be adapted and extended for the communication of different kinds of influences, for simplicity 60 there is disclosed in this case an arrangement adapted to communicate only one stopping influence. Also, while such stopping influence may be employed to initiate or otherwise govern the operation of any suitable form of brake control or cab signal apparatus, for the purpose of explaining the nature and mode of operation of this invention, consideration is limited to two types or forms of train control systems, 65 namely, a permissive or semi-automatic system in which a brake application is initiated at each distant or caution signal unless the engineer takes appropriate action to prevent or hold off such brake application, and an 70 automatic stop system employing an overlap, in which an absolute and unpreventable brake application is produced at each of the two danger or stop signals in the rear of a train. 75

The various specific objects, characteristic features, and advantages of the invention will be in part apparent and in part pointed out as the description of the specific embodiments progresses. 80

In describing the invention in detail, reference will be made to the accompanying drawings, in which:—

Figure 1 is a simplified and diagrammatic view showing in accordance with established 90 convention one typical arrangement of trackway circuits adapted to control the track elements of this invention to provide an automatic stop system with overlap;

Fig. 2 illustrates the car equipment designed and adapted to be used in connection with the automatic stop trackway system shown in Fig. 1; and 95

Fig. 3 is a continuation of Fig. 1 and shows the trackway circuits and devices for 100 providing an absolute stop at an interlocked signal.

This is a division of application Ser. No. 531,903, filed Jan. 26, 1922, and covers an

automatic stop system with overlap and with the provision of an absolute stop at interlocked signals.

5 *Trackway apparatus (automatic block territory).*

In the automatic stop type of system under consideration, since an unpreventable brake application automatically occurs if 10 the train should pass a stop signal, and since it is necessary, to meet practical operating requirements, for the train in case of emergency to be able to pass a stop signal, some scheme for permitting a train to get by a 15 stop signal without an automatic brake application is desirable, provided appropriate action to safeguard the train has been taken. While various arrangements of "key-by" devices and circuits, acting upon either the 20 track apparatus or the car apparatus, may be employed, there is disclosed in accordance with this invention an arrangement in which a train is allowed to pass a stop signal without a brake application at some selected 25 minimum speed. In other words, after a train has slowed down, or stopped in obedience to a danger or stop signal, in conformity with the rules, it may pull by that stop signal at a slow speed without receiving a 30 stopping influence.

The system of automatic stop with overlap is well adapted for use on subways, elevated lines, interurban lines, and the like. The 35 trains on such railroads commonly include a number of motor cars, each equipped with train control devices and the same control equipment, so that any motor car may be used at the head end of the train. In the 40 interests of safety, it is desirable that the train control equipment on each of the motor cars of such multi-car trains should be effective to govern the train as a whole, otherwise an adequate car cut-out device must be 45 provided for the rear cars, and such device may be improperly or carelessly manipulated to cut out of service all of the motor cars on a train and leave it without any protection. If this is done, then, on account of the fact 50 that each one of the several motor cars in a train is capable of active cooperation with a track element in its stopping condition, it becomes necessary to provide some sort of a so-called retaining circuit which allows a 55 multi-car train of this kind to pass a track element without stopping itself.

60 *Trackway circuits.*—One simple arrangement of trackway circuits adapted to conform with the above requirements employing neutral home and distant relays, is shown in Fig. 1 as a typical illustration of an overlap block signal system and associated control devices. Referring to Fig. 1, the railway track is divided by insulated 65 joints 2 into blocks in the usual manner. In the arrangement shown, a so-called one-rail

track circuit is employed, leaving the other rail free for the return of propulsion current in electrically propelled railroads; but it should be understood that the regular two-rail track circuit for steam roads may be 70 used, or a two-rail track circuit with impedance bonds for electrically propelled roads, all in accordance with well recognized practice. For simplicity, a direct current 75 block signal system has been shown, but by the use of a transmission line, transformers, alternating current relays and other expedients well-known in the art, the same scheme of connections of track elements may be employed in conjunction with an alternating current block signal system. The individual rails are bonded together by bonds in the usual manner, the blocks V and W and the adjacent ends of two other blocks U and X being shown. The parts and circuits associated with the various blocks are the same, at least in ordinary block signal territory, and for convenience have been given like 80 reference characters with distinctive 85 exponents.

89 Each of the blocks is provided with a track relay 4 at one end and a source of energy, which has been illustrated as a battery 3, at the other end. This system preferably forms an adjunct to some form of block 95 signal system, and in the particular embodiment it has been shown in connection with color-light signals.

99 Besides the track relay 4, each block is 100 provided with a home relay H and a distant relay D. These relays are of the usual type, the relay H having one of its contacts particularly designed and adjusted to function 105 slightly different from the other, or standard contacts. In order to assure that a back contact of the track relay 4 will make before the front contact of the relay H breaks, this relay being controlled by a front contact of the track relay, the front contact 188 110 of the track relay 4 has been designed to function as a long-wipe contact. This contact 188 has been illustrated conventionally by a stationary contact shown by an arrow, and a movable contact comprising a resilient 115 finger. It is apparent that when such track relay is energized and then deenergized the contact 188 will not break its circuit until after a short lapse of time after the usual or standard back contacts of the track relay 120 have closed. It is, therefore, apparent that by proper design of this long-wipe contact, its operation as compared with the operation of the usual contacts will be such that a standard back contact will make about the same time, or even earlier than such long-wipe front contact breaks. The purpose is to make the front contact 189 of the home 125 relay open later than the closing of back contact 190 of the track relay; and, if it is desired, the front contact 189 of the home 130

relay H may also be made to function as a long-wipe contact to further delay its opening as the track relay is deenergized.

For convenience the circuits are shown 5 in accordance with the convention in which BW indicates a battery wire and CW a common wire, which in practice runs along the track, or an equivalent connection to a local battery. It should be understood that 10 these connections BW and CW may lead to the same or different batteries of appropriate voltage, all as well-known in the art.

The circuit for energizing the home relay H of block V may be traced as follows:— 15 commencing at CW, relay H, wire 191, front contact 188 of track relay 4, wire 192, front contact 193¹ of track relay 4¹ of block W.

The circuit for energizing the distant relay D of block V may be traced as follows:—commencing at CW, relay D, wire 194, front contact 195 of home relay H, wire 196, front contact 197¹ of home relay H¹ of block W.

At the entrance of each block is located 25 a pair of track elements T, each of which in the particular form illustrated comprises a U-shaped core or yoke of magnetic material and a coil 16 surrounding the back portion of said core, as shown. The U-shaped core is preferably laminated to reduce the flow of eddy currents upon rapid changes of flux through the core, and terminates in upstanding poles having enlarged pole pieces. In practice these track elements 30 are housed in non-magnetic housings, having sloping or ramped approaches (not shown) so as to protect them from the weather and from dragging equipment of passing trains. These track elements T are preferably located outside the running rails and 35 extend a considerable distance above the track rails, so that they have an influence transmitting advantage over crossing rails and certain other magnetic bodies along the trackway. Although these track elements T may be located directly opposite each other on opposite sides of the track, they have been shown arranged diagonally with 40 respect to the trackway. This diagonal arrangement of the track elements follows from a similar arrangement of the car elements on the railway vehicle. In this system it is desirable to have the car elements mounted on the trucks of a motor car, and 45 also to have the car elements mounted symmetrically with respect to the first axle of a car regardless of which end of the car is leading. Consequently, one of the car elements is fastened to the right-hand side of 50 the front truck, when facing in one direction; and the other car element is located on the right of the forward truck, when the car is headed in the other direction, thus 55 making a symmetrical arrangement of the car element with respect to either end axle.

of the vehicle. The reason for this symmetrical arrangement of the car elements with respect to the front axle of either end of the vehicle will be given in the description of the operation.

70

The coils 16 of these track elements T are connected in series in a manner dependent upon the car apparatus which is to cooperate therewith, but are in each event connected so that the E. M. F.'s generated when 75 a pair of cooperating car elements passes thereby will be cumulative. The circuit including the coils 16 of the two track elements T in series may be traced as follows:—coil 16 of the track element T, wire 80 198, coil 16 of the other track element T, wires 199 and 200, front contact 198 of home relay H, and wires 201 and 202 back to coil 16; and in multiple with the front contact 189 of the home relay H is another partial 85 circuit comprising the wire 203, back contact 190 of track relay 4, and wire 204. Thus the coils 16 of the track elements T will be included in a circuit of preferably low resistance, either when the home relay H is 90 energized, or when the track relay 4 is deenergized.

A three-aspect light signal has been illustrated conventionally by red, yellow, and green lamps, r, y and g, respectively. This light signal is controlled by the home and distant relays H and D by the circuits shown by dot and dash lines. Since the condition of the light signal is readily apparent when the position of the relays H and D is known, no further description thereof is 95 considered necessary.

Operation of trackway apparatus shown in Fig. 1.—The track devices in Fig. 1 are illustrated in their normal or clear traffic condition, and under this condition the relays H and D will be energized, thus completing the circuit through the lamp g indicating a clear traffic condition and maintaining the coils 16 of the track element T in 100 a closed circuit of low resistance through the front contact 189 of the relay H, thus putting the track elements in their normal, 105 clear or non-stopping condition.

Under these normal conditions, let us assume that a train is in the block U, traveling in the direction of traffic indicated by the arrow and enters the block V. The presence of the train in the block V will shunt the 110 track relay 4, thus causing it to drop its armature, thereby closing the back contact 190 and opening the front contact 188. Since the contact 188 is of the long-wipe type, the circuit will be made by the contact 190 before the contact 189 is opened, thus insuring the making of the circuit through the coils 16 of the track elements through the contact 190 before this circuit is broken by the front contact 189 controlled by the relay 115 H which has just been deenergized by the 120

125

130

opening of the front contact 188 of the relay 4. The object in making the front contact 188 retarded is to insure the making of the back contact 190 before the front contact 5 189 breaks the circuit through the coils 16 of the track elements, and is for the purpose of providing "retaining means", the object of which has hereinbefore been explained, that is, the first car entering a 10 clear block will not put the track elements T in their stopping condition, which might cause the train to be stopped by the car-carried apparatus of the following cars of such multi-car trains as have been referred 15 to in this particular system.

The distant relay D is deenergized when home relay H drops, because its energizing circuit is broken at front contact 195. The de-energization of relays D and H will, of 20 course, change the aspect of the light signal to indicate red, but since this is an obvious result which may readily be determined by tracing the dot and dash lines in the drawings, no tracing of these particular 25 circuits for controlling the light signal is deemed necessary.

With the block V occupied, no train is apt to be in block U, at least not one that is moving at a high rate of speed, because 30 it would have had to pass a danger signal at the entrance of block U, which block was also protected by track elements in their danger condition at that time as will become evident as the description of the operation 35 progresses. If, however, a train would move from the block U into the block V while the block V is occupied, no stopping influence will be transmitted to the car apparatus, because the track elements at the entrance of 40 the block V have their coils in a closed circuit, that is, in their clear condition. This feature of this system is, however, harmless since this is a one block overlap system, and the engineer must pass a caution signal and 45 two successive danger signals, adjacent one of which the track devices are in their danger condition, before the occupied block is reached.

Assume now that the train has left the 50 block V and has entered the block W. The devices at the entrance of the block W will now assume the same condition as the corresponding devices at the entrance of the block V when said train entered the block 55 V. Since the train has passed entirely out of the block V, the track relay 4 will become energized, thus closing its contact 188 and opening its contact 190. The closing of the contact 188 will not energize the relay 60 H, because its energizing circuit is interrupted at the contact 193¹ of the track relay 4¹ of block W, therefore leaving the contact 189 open, and consequently the opening of the contact 190 will put the track elements 65 into their danger condition. The dis-

tant relay D will not be affected by the passage of the train from the block V into the block W, and since neither of the relays H and D is energized, the three-aspect color-light signal at the entrance of block V will 70 not be changed by the movement of the train from the block V into the block W, and will therefore still indicate red or danger.

Assume now that the train which is considered to be occupying block W has moved 75 entirely into the block X. Under these conditions the home relay H at the entrance of the block V will be energized, because its energizing circuit will be completed at the front contact 193¹ of the track relay 4¹ at the 80 entrance of the block W, because this relay will be picked up at the time the train leaves the block W. The energization of the home relay H will cause the contact 189 to be closed, thus putting the track elements at the 85 entrance of the block V in their clear traffic condition. The energization of the home relay H will close the contact 195 in the energizing circuit of the distant relay D. This relay D will, however, not be energized, because its energizing circuit is open at the 90 contact 197¹ of the home relay H¹ at the entrance of the block W, this home relay H¹ being deenergized because its energizing circuit is open at the front contact 193₂ of the 95 track relay 4², this track relay in turn being deenergized on account of the presence of the train in block X.

It should be noted that the presence of a train in the block X with the blocks U, V 100 and W unoccupied causes the light signals at the entrance of the blocks W and X to indicate danger, at the entrance of the block V to indicate caution and at the entrance of the block U to indicate clear.

Assume now, with the train in the block X, that another train is approaching the block U in the direction of the arrow. Since the signal at the entrance to block U is at clear, the train will continue its 105 normal speed until it approaches the entrance of the block V. As the train approaches the entrance of the block V, the engineer will observe a caution signal indicating that he may proceed into the block V prepared to stop at the end of the block. The track elements T, T at the entrance of the block V are in their clear traffic condition. The train, having passed a caution signal now, may proceed under caution in the block 110 V, but if it enters the block W, which has its signal at danger and its track elements in their danger condition, the train will be stopped when passing said track elements by suitable apparatus on the vehicle to be 115 described hereinafter.

Speed control.—If the engineer, however, has observed the caution signal and has reduced the speed of the train to a pre-determined extent, say to five miles per hour, 120

he may pass into the block W without receiving such a danger or stopping influence. This is due to the fact that the first axle of the train will bridge the rails of the block W, thus deenergizing the track relay 4¹, causing the back contact 190² of the track relay 4¹ to be closed a short time after such deenergization. In a relay of the usual construction, the time necessary for its contacts to complete their movement is in the neighborhood of four-tenths of a second; and consequently the track elements at the entrance of the block W will be put in their clear or short-circuited condition about four-tenths of a second after the first axle enters the block W. These track elements are so located with respect to the insulated joint 2 at the entrance of said block that a train, moving at the predetermined speed heretofore mentioned, say five miles per hour, will have its car-carried elements directly over the track element four-tenths of a second after it enters the block. Therefore, a train entering the block at a speed not higher than five miles per hour, will allow sufficient time to elapse for the contact 190² of the track relay 4¹ to close, thereby putting the track elements in their clear condition before the car elements pass thereby. If, however, the train enters the block at a higher speed than five miles per hour, insufficient time will have elapsed to allow the contact 190² to close, consequently bringing the car elements by the track elements before they are in their clear condition, thus transmitting a stopping influence to the car apparatus. Although practical results have been obtained by the use of relays of the usual construction, and not provided with any retarding devices, such retarded or slow acting relays may be used instead.

Structure of car apparatus in Fig. 2.—One particular arrangement of car apparatus and circuits for causing an absolute and unpreventable brake application after an influence has been transmitted thereto, and particularly adapted to the one block overlap trackway system just described, has been illustrated in Fig. 2. In this system of car apparatus, two car elements L and L¹ arranged diagonally on opposite sides of the car are provided. These elements L—L¹ comprise U-shaped cores terminating in enlarged pole pieces having a primary coil P on one leg thereof and a secondary coil S on the other leg. These secondary coils S and S¹ are connected in series so that their effect is cumulative.

The car elements L—L¹ are disposed diagonally opposite each other for the purpose of arranging them symmetrically with respect to either end axle of the car, for the reasons previously explained. This system employs three relays, namely, a main control relay C which is provided with light

moving parts, thus operating on little energy changes, a repeater relay R which is actuated by the main relay but is of a heavier construction, thereby permitting the control of larger currents thereby; and a check relay CR arranged in series with the primary coils P—P¹ of the car elements, so that if the circuit through these primary coils is entirely interrupted, or if the current depreciates to an extent below a value necessary to make these car elements function, this check relay will drop its armature 205 and through intervening mechanism apply the brakes. These relays are designed for the particular purpose for which they are to be used and are preferably provided with balanced moving parts, so that they will not be apt to be actuated by jars, vibrations, and the like.

The brake control device comprises an electro-pneumatic valve E. P. V. which is constructed to vent the train pipe directly when its winding 206 is deenergized, and is provided with two pairs of make-before-break spring contacts 207 and 208 which are opened and closed respectively when this E. P. V. is deenergized. The valve construction of this E. P. V. may be such as to effect a service brake application, or an emergency brake application, as desired, this being dependent upon the size of the valve opening when the E. P. V. is deenergized.

Another part of this particular car-carried apparatus comprises a pneumatically operated switch, for convenience called an air-switch. This air-switch AS consists of a cylinder 209 of suitable size, having its closed end connected to the brake pipe BP. This cylinder 209 is provided with a piston 210 making an upper air-tight chamber, and having a piston rod 211 extending therefrom through the other end of the cylinder. In order to permit atmospheric pressure to bear against the under side of the piston 210, air vents 212 have been provided. The other end of this piston rod 211 has an insulated movable contact 213, adapted to contact with the stationary contacts illustrated as arrows when the piston 210 is raised. The raising of 210 is due to the spring 214 on the piston rod 211 between the piston 210 and one end of the cylinder. Under normal conditions, that is, with running brake pipe pressure in the cylinder 209, the spring 214 will be compressed, thus moving the movable contact 213 away from the stationary contacts. If now the pressure in the brake pipe BP is reduced to a predetermined extent, this spring 214 will move the piston 210 against the pressure in the brake pipe, thereby bringing the movable contact 213 against the stationary contacts. The spring 214 is preferably of such strength that the air-switch will not close until after a lapse of time following the necessary vent-

ing of the brake pipe, which is long enough to assure that the train has come to a stop from its maximum attainable speed. In practice, this desired time control is obtained by venting the brake pipe pressure to such a low value that the required time is consumed in venting the brake pipe below that necessary to effect a full service brake application, so that the train is stopped before contact 213 closes.

This particular car apparatus is provided with two batteries, namely, a main battery 215 and a small secondary or relay battery 216. The main battery 215 is assumed to be the source of energy commonly used in a multi-car system for the purpose of operating the multiple-unit control system, doors, bells, and a reserve source of energy for illumination. Such a battery is usually floated across the third rail in the case of electrically propelled vehicles, and its voltage varies considerably. The small battery 216 is provided to give a more constant potential source of supply for the purpose of energizing the main control relay C and the repeater relay R. In this system a reset bus 217 has been provided, whereby the control apparatus on any one of a plurality of connected motor cars may be reset from any one of the cars; and although in the particular system herein described, it is seldom necessary to reset more than the apparatus on the first car, it is nevertheless desirable to be able to reset the apparatus on any car in the particular train from the motorman's cab in use at that time. A reset push button 218 is located in each motorman's cab at a convenient place. The operation of this reset button 218 and bus 217 will be explained in the operation of the car apparatus.

The energizing circuit for the main control relay C may be traced as follows:—beginning at the positive side of the small or relay battery 216, wire 219, front contact 205 of check relay CR, wire 220, armature 221, and front contact 222 of main relay C, wires 223 and 224, secondary coil S¹, wire 225, secondary coil S, wire 226, winding of main relay C, wires 227 to 230, winding of check relay CR, wires 231 and 232, and back to the negative side of the small battery.

The circuit for energizing the repeater relay R may be traced as follows:—starting at the positive side of the small battery 216, wire 219, front contact 205 of check relay CR, wire 220, armature 221 and front contact 233 of main relay C, wire 234, winding of repeater relay R, wires 235, 229 and 230, winding of the check relay CR, wires 231 and 232, and back to the negative side of the small battery.

The energizing circuit of the primary coils P and P¹ may be traced as follows:—beginning at the positive side of the large

battery 215, wires 236 and 237, primary coil P, wire 238, primary coil P¹, wires 239 and 231, winding of check relay CR, wires 230, 229, 228, 240 and 241, and back to the negative side of the large battery. 70

The energizing circuit for the winding 206 of the E. P. V. may be traced as follows:—starting at the positive side of the main battery 215, wires 236, 242 and 243, front contact 207 of the E. P. V., wires 244 and 245, front contact 246 of the repeater relay R, wire 247, winding 206 of the E. P. V., wires 248, 229, 228, 240 and 241 and back to the negative side of the battery. 75

It is thus seen that the energizing current 80 of the primary coils P and P¹ flows through the winding of the check relay CR in one direction, and that the current for energizing the main control relay C and the repeater relay R flows through the winding of 85 the check relay CR in the other direction. Since the current in the primary circuit is much larger than the current for supplying the relays C and R, it is obvious that a voltage drop due to this primary current 90 will result across the winding of the relay CR, and that this voltage drop will be in a direction to increase the voltage across the relays C and R. Thus, when a voltage of the main battery 215 increases, due to an 95 increase of voltage on the trolley or third rail across which this battery floats, the current flowing in the primary circuit will be likewise increased, and this increase in current will cause a slight increase in voltage 100 across the relays C and R, thereby compensating to a certain extent the voltage across the relays C and R when a voltage change takes place across the primary coils in the primary circuit. Such a compensation is 105 desirable because the induced voltage in the secondary coils S and S¹, which opposes the voltage of the small battery 216, as will appear hereinafter, is dependent upon the strength of the magnetic fields produced 110 by the primary coils P and P¹, and therefore it is desirable to change the potential across the relay C in a definite relation to a change of magneto-motive-force produced by the primary coils of the car elements. 115

Operation of car apparatus in Fig. 2.—Assume now that a car equipped with the apparatus illustrated in Fig. 2 is moving between control points with this apparatus in its normal condition as illustrated, that is, with the relays C, R and CR, the winding of the E. P. V., and the primary coils P and P¹ energized through the circuits heretofore traced; and that this car apparatus passes over a pair of track elements T in 120 their danger condition, that is, with their windings 16 open circuited. This cooperation of the car-carried elements and the track elements T causes the flux passing through the secondary coils S and S¹ to 125 130

- greatly increase. This increase of the flux through the secondary coils is believed to be due to both an increase in the total flux through the primary coils and a diversion of flux from leakage paths. As the car element recedes from the track element, a corresponding decrease of flux through the secondary coils takes place. The rapid momentary increase and decrease of the flux 5 through the cores of the car elements induces a voltage in the secondary coils S and S¹ similar to a single cycle of alternating current, these secondary coils being so connected that these induced voltages are cumulative, and are so connected in the circuit with the small battery 216 that the first wave of the single cycle of E. M. F. is in opposition to the voltage produced by the small battery and the resistance drop across the 10 check relay CR. This first wave of the voltage generated in the secondary coils S and S¹ decreases the current in the main control relay C to a sufficient extent to cause it to drop its armature 221 and open both of 15 its front contacts, thus entirely interrupting its energizing circuit and also the energizing circuit of the repeater relay R, these circuits having been heretofore traced.
- The deenergization of the repeater relay 20 R causes its front contact 246 to open and interrupt the energizing circuit of the E. P. V., which, when deenergized, will vent the brake pipe BP and apply the brakes to bring the train to a stop. During such 25 venting of the brake pipe BP the brake pipe pressure will gradually decrease, and when it has decreased to the predetermined extent for which the spring 214 in the air-switch AS has been designed said switch 30 will be closed, thus shunting the front contact 222 of the main relay C, thereby picking up this relay which will stay energized through said front contact as soon as it is picked up (this being a stick relay). As 35 soon as the main relay C is energized its other front contact 233 will complete the energizing circuit for the repeater relay R, thus causing it to close its front contact 246. The closing of this front contact 40 of the repeater relay R will, however, not energize the E. P. V., because this E. P. V. is likewise of the stick type, its energizing circuit being interrupted at its own front contacts 207.
- To energize the E. P. V., the reset button 45 218 in any one of the motorman's cabs of a multi-unit train is closed. This closes a pick-up circuit that may be traced as follows:—beginning at the positive side of the 50 large battery 215 located on the car in question, wires 236, 242, and 249, reset button 218 located on the car in question, wire 250, reset bus 217, through the following apparatus on any one of the cars in the train, wire 251, back contact 208 of the E. P. V.,
- wires 252 and 245, front contact 246 of the repeater relay R, wire 247, winding 206 of the E. P. V., wires 248, 229, 228, 240 and 253, to the ground and back through the rails of the track to the ground connection 70 on the particular car whose reset button has been operated, thence wires 253 and 241 back to battery 215.
- It should be noted that the contacts 207 and 208 operated by the E. P. V. are of the 75 spring type, and are so designed that the top or front contacts 207 make as the E. P. V. is energized before the back or bottom contacts 208 break. This is done in order to permit the stick circuit of the E. P. V. to be closed before the pick-up circuit thereof is interrupted by the back contacts 208 of the E. P. V.
- If the coils 16 of the track elements T are 80 in a closed circuit of low resistance, no effect is produced on the car apparatus because there is insufficient change of flux through the secondary coils to cause operation of the control relay C. This is attributed to the fact that the coil 16 on the core 85 of each track element T, being in a closed circuit of low resistance acts as a choke coil to oppose or choke back the passage of flux through said core. Putting it another way, as soon as the primary coil P tries to 90 send flux through the core 15 of the track element T, this changing flux induces in the coil 16 a voltage that, in accordance with well known principles, tends to send a current in a direction to create a field opposing the flux inducing such voltage. In any event, it is found that by selecting the proper number of turns for the coil 16 of the track element, with regard to the strength of the primary field, sensitiveness of 95 the relay C, and other factors, an organization may be obtained in which the inclusion of the coil 16 in a circuit of relatively low resistance permits passage of the car element without operation of the control relay 100 105 C, whereas, with this coil open circuited, said relay will be operated.
- Some of the features of advantage of this system are that the voltage across the main control relay C is automatically compensated 110 as the energizing current through the primary coils P—P¹ of the car elements changes, the check relay CR serving both to check the integrity of the primary circuit and assure the flow of sufficient current 115 therein to make the car elements function properly, and also as a compensating resistance for automatically compensating for fluctuation in the main battery voltage, as explained. The system can only be reset, after an automatic brake application has been made, after a sufficient time has elapsed 120 and a sufficient brake pipe pressure reduction has been made.
- Absolute stop at interlocked signals.—A* 125

- particular system of car apparatus for causing an absolute and unpreventable stop when a stopping influence has been transmitted thereto has just been described in 5 connection with a trackway system, comprising an overlap and having means whereby a control influence will not be transmitted to the car apparatus unless the vehicle passes a stop signal above a predetermined 10 speed, taken, for example, at five miles per hour. A system of this kind is satisfactory for ordinary block signal territory, but is not desirable where an absolute stop is necessary, such as at the entrance of an 15 interlocking plant or like conflicting route where a train shall not pass a stop signal at any speed, because it may get in the way of a fast moving train using a conflicting route.
- 20 For a semi-automatic train control system the desired absolute control at an interlocked signal may be obtained by using regular derail devices, but such devices have some 25 objections and are not applicable to subways or elevated railway systems for reasons apparent to those skilled in the art, and it is therefore desirable to provide an 30 arrangement by which the train will be stopped by an unpreventable brake application if it attempts to pass an interlocked signal in its stopping or danger position. This may be accomplished by locating one 35 or more inert track elements directly opposite the signal, so that while the train may pull up to the signal, the E. P. V. would be 40 operated and the brakes automatically applied if the train attempts to pass such signal at stop. As previously explained, communication of stopping influences are 45 dependent upon change of flux, requiring certain relative motion between the car and track element; and although this action may take place at a very low speed depending upon the design of this apparatus, if desired, an absolute stop element acting at the 50 lowest possible speed may be employed in addition to, or as a substitute for, the regular inert element at the interlocked signal.
- 55 For the purpose of explaining the nature and mode of operation of an arrangement embodying this invention for enforcing an absolute brake application at an interlocked signal at the lowest possible speed, there are shown in Fig. 3 in a simplified and diagrammatic manner two intersecting stretches of track, together with track devices and circuits, which have been selected as a typical 60 illustration of the control for the conflicting routes found in interlocked territory. One 65 track, comprising blocks Y and Z, for convenience called the main track, may be considered to be a continuation of the stretch of track shown in Fig. 1. It is contemplated that the same arrangement and control of track elements and signals, that has

been shown in Fig. 1 and hereinbefore described, will be used on the two stretches of track shown in Fig. 3; but to avoid complication, the description of some of the circuits for carrying out said scheme of automatic stop with overlap has been omitted.

70 The signals, track elements and control circuits associated with the two intersecting stretches of track in Fig. 3 are the same; and for convenience the relays and other devices thereof are given the same reference characters as in Fig. 1, with exponents 4 and 5 added. The additional devices used to obtain the absolute stop control, being the same for the block Z, and the block Z-Z, 75 80 will be given the same reference characters with the distinguishing exponent "a."

85 At a distance from the point of intersection of the conflicting routes, shown as the entrance to the blocks Z and Z-Z, are home signals, which are the color light signals, the same as used in block signal territory, and which govern traffic over the respective routes in the direction indicated by the arrows. These home signals are controlled in 90 conformity with established interlocking practice, both by track circuits and also by levers and associated equipment at a central point or tower 254. The levers for the 95 home signals in question have been shown for the sake of simplicity in the form of push buttons 255-255^a. These levers are mechanically interlocked in the usual way, and are provided with electric locks, indication mechanism, and other devices common in 100 modern interlocking practice.

105 At each home signal is located a pair of track elements T, the same as used in block signal territory (Fig. 1), and a pair of additional or auxiliary track elements TS designed to assure the transmission of a stopping impulse at the lowest possible speed of the train. The auxiliary track elements TS 110 constitute similar magnetic cores and coils and these coils are at times energized by alternating current of a commercial frequency, shown in this instance as derived from transformers 256-256^a, the primaries of which are connected to a suitable source of alternating current (not shown). For the 115 purpose of checking the integrity of the energizing circuit for the auxiliary track elements TS, so as to be sure of a control of train movement on the side of safety in the event of a circuit failure, there are provided 120 check relays 257-257^a, of the usual alternating current type, which may be located in the tower 254, as shown, or at some other convenient place.

125 *Operation of Fig. 3.*—The mode of operation for train movements over either of the intersecting stretches of track shown in Fig. 3 is the same, and a description of a movement over the main stretch of track comprising blocks Y and Z, will by analogy ap-

- ply to the other stretch. Normally, in accordance with common practice, the home relay H^4 of the block Z is deenergized, the home signal at the entrance to this block indicates danger or stop, and the corresponding track elements T^4 and TS are in the active stopping condition. In the case of the regular track elements T^4 , this stopping condition is due to the fact that their coils 16⁴ 5 are open circuited at the front contact 189⁴ of the home relay H^4 , since the lever 255 is in its normal position and the energizing circuit for said home relay is broken at the normally opened contacts 258 of said lever. 10 This energizing circuit of the home relay H^4 may be traced as follows:—commencing at the common wire CW, relay H^4 , wire 191⁴, front contact 188⁴ of track relay 4⁴, wire 192⁴, front contact 259^a of check relay 257^a, 15 wire 260, contacts 258 of lever 255, wire 261, and thence through a front contact of the track relay of the block next in advance of the block Z (not shown).

The auxiliary track elements TS of the block Z are normally energized by alternating current, due to the existence of a circuit which may be traced as follows:—commencing at one terminal of the coil of the upper or lefthand track element TS, wires 262 and 263, secondary of transformer 256, wire 264, check relay 257, wire 265, contacts 266 of lever 255, wire 267, back contact 268, of home relay H^4 , wires 269 and 270, coil of track element TS, and wire 271 to the coil of the first 20 mentioned track element TS.

It will be noted that this energizing circuit includes the check relay 257 which, as shown by analogy to the energizing circuit for the home relay H^4 above traced, governs the energizing circuit for the home relay H^5 of the conflicting route, so that the home relay of said conflicting route can not be energized to clear the signal and allow the passage of a train unless the track elements TS 25 are actually energized by alternating current, the existence of such energization being indicated by the fact that the check relay 257 is picked up. Likewise, the track elements TS^a are normally energized by alternating current and pick up the check relay 257^a, which governs the energizing circuit for the home relay H^4 .

Under the normal conditions above described, the regular track elements T^4 , being open circuited, will effectively stop a train attempting to enter the block Z at a speed sufficiently high to induce enough voltage in the secondary coils of the car elements to actuate the brake control apparatus. The exact speed at which this stopping action will occur depends of course upon the size and proportion of the parts, length of the air gap, and the like; and while by appropriate design, such stopping action may be caused to take place any speed above a very

low speed, such as three or four miles per hour, the auxiliary track devices TS, being energized by alternating current, will act to cause a stopping influence at the slowest possible speed, and even when the car element stands stationary over these track elements. It will be readily appreciated that such action is due to the fact that the alternating flux produced by the track elements TS will alternately oppose and assist the flux of the primary coil on the car, and regardless of relative motion, induces voltage changes in the secondary coil that will at times oppose the voltage in circuit with the main control relay, thereby causing it to drop and apply the brakes, in the manner hereinbefore explained.

Assume now that the operator in the tower 254 desires to clear the route over the main track comprising blocks Y and Z. He reverses the lever 255, opening contacts 266 and closing contacts 258. The opening of contacts 266 breaks the energizing circuit for supply alternating current to the track elements TS; and the closing of contacts 258 closes a break in the energizing circuit for the home relay H^4 . If the track elements TS^a at the entrance to the block Z—Z of the conflicting route, or routes, are energized with alternating current and the corresponding check relay 257^a is picked up, then the home relay H^4 is energized, assuming that the track circuits controlling said relay are not occupied. The energization of the home relay H^4 completes the circuit for the distant relay D⁴ at the front contact 195⁴, thereby clearing the signal of block Z. The energization of the relay H^4 similarly causes clearing of the signals at the entrance to the blocks X and Y, in the manner previously explained.

When the home relay H^4 picks up, its front contact 189⁴ closes and puts the track elements T^4 in their clear condition by establishing a closed circuit for the coils 16⁴ 110 of said track elements. Also, the front contact 268 of the relay H^4 closes and establishes a low resistance circuit for the coils of the auxiliary track elements TS, which may be traced as follows:—commencing at the upper element TS, wires 262, 272 and 273, front contact 268, wires 269 and 270, coil of other elements TS, and wire 271. Trains may now pass through the block Z 115 without receiving an automatic brake application.

A train entering the block Z will put to stop the signals and track elements T^4 in the rear in the same way as in block signal territory; but until the operator shifts the lever 255 back to the normal position, the track elements TS are not energized, because under the conditions described, that is, under conditions when there is no danger 120 on account of trains on the conflicting route,

only the regular control for block signal territory is required.

- Since it is assumed that multi-car trains will be employed, an arrangement of retaining circuits is provided for the track elements at the entrance to the blocks Z and Z-Z to hold these track elements in the clear condition as the first car enters these blocks, in order to avoid premature stopping of some of the rear cars. In the case of the regular track elements T, this retaining is accomplished in the same way as previously explained, that is, by providing a shunt for the coils of the track elements T controlled by the back contact 190⁴ of the track relay 4⁴. In the case of the auxiliary track elements TS, there is provided a similar shunt for their coils controlled by an additional back contact 274 of the track relay and comprising wires 275 and 276.

The low speed "key-by" feature hereinbefore explained in connection with automatic block signal territory in Fig. 1 is not, however, used in connection with the track elements T⁴ and TS at the entrance to the blocks Z and Z-Z; and both pairs of these track elements are so located with respect to the insulated joints that they will be encountered by the car elements of a passing vehicle before the first axle of that vehicle passes over said joints, or at least before the back contact of the track relay closes. Such specific location is, of course, selected with due regard to the customary practice of allowing a train to pull completely up to the signal; and if necessary, the signal may be located a short distance in the rear of the insulated joints.

One of the important features of the absolute stop arrangement shown in Fig. 3 consists in the provisions made for checking the supply of alternating current to the auxiliary track elements TS. It is contemplated that this alternating current will be derived from a reliable source, with one or more independent sources in reserve, so that aside from local circuit or contact failure, each pair of auxiliary track elements TS throughout the interlocking plant will always be energized with alternating current, when desired to block train movement. The application of alternating current to each individual pair of these track elements TS is automatically checked by a check relay 257; and unless this check relay is energized, the signals and train control track elements of any conflicting routes can not be cleared. In the event of a current failure after a route has been set up, a contingency that is far remote, the check relay 257 will automatically detect such failure and at once put to stop the signals and track devices of any conflicting route that may be clear, thereby at once stopping train movement on this conflicting route.

While there have been shown and described various specific constructions and arrangements of parts and circuits for practicing the invention, and the mode of operation and many of the advantageous features of these constructions have been pointed out, it should be understood that this disclosure does not exhaust all of the various embodiments of the invention, nor include the various auxiliary devices and methods of signal and train operation well known in the art and commonly practiced. The specific disclosure herein is, therefore, susceptible of considerable adaptation and modification in practice, without departing from the invention.

What I claim is:—

1. A train control system of the type in which control influences are transmitted from the trackway to the vehicle through an intervening air gap comprising, an impulse receiving stick relay, a train control device connected in a stick circuit governable by said relay, automatic means effective only after the train has been brought to a stop for resetting said stick relay, and manual means for resetting said train control device.

2. A train control system of the type in which control influences are transmitted from the trackway to the vehicle through an intervening air gap comprising, an impulse receiving stick relay, a train control device connected in a stick circuit governable by said relay, pressure responsive means for resetting said stick relay, and manually operable means for resetting said train control device.

3. A train control system of the type in which control influences are transmitted from the trackway to the vehicle through an intervening air gap comprising, an impulse receiving stick relay, a train control device connected in a stick circuit governable by said stick relay, and manually operable means for resetting said train control device, said manually operable means only being effectual when said train control device is in its operative position.

4. A train control system of the type in which control influences are transmitted from the trackway to the vehicle through an intervening air gap comprising, a car-carried element consisting of a core having a primary winding, a source of current for energizing said winding, a secondary winding on said core connected in series with an electro-responsive device for controlling the brakes of the vehicle, and another source of energy including means for varying its voltage in a definite relation to the variation of the voltage of the first mentioned source.

5. A train control system of the type in which control influences are transmitted

from the trackway to the vehicle through an intervening air gap including, an electrical-
ly operated brake control device normally
energized through front contacts controlled
by said device, and means for reenergizing
said device when deenergized through a cir-
cuit including back contacts of said device,
said front and back contacts both being
completed at an intervening point of the
movement of said device to its energized
position.

6. In a train control system, the combina-
tion of a car-carried element comprising, a
core of magnetic material provided with a
normally energized primary winding and a
secondary winding, brake control apparatus
controlled by said secondary winding; and
trackway devices magnetically cooperating
with said core for transmitting controlling
influences to said car-carried element com-
prising one track element consisting of a
dead magnetic core when in its influence
transmitting condition, and another track
element consisting of a core of magnetic
material having a coil thereon energized by
alternating current when in its influence
transmitting condition.

7. A train control system of the type in
which control influences are transmitted
from the trackway to the vehicle electro-
magnetically comprising, a car-carried ele-
ment consisting of a magnetic core having
an influence receiving winding thereon, a
stick relay having its stick circuit connected
to said winding, brake control apparatus
controlled by said relay, a trackway element
consisting of a core having legs extending
above the top of the track rails and having
a winding thereon energized by alternating
current when in its influence transmitting
condition for effecting the winding of said
car-carried element to drop said stick relay
when said car-carried and trackway ele-
ments cooperate, and pressure responsive
means for resetting said stick relay.

8. In a train control system of the type
in which control influences are transmitted
electro-magnetically through an intervening
air gap, car-carried apparatus including in-
fluence receiving means, and brake control
apparatus governed thereby; and trackway
means comprising track elements for trans-
mitting control influences to said influence
receiving means, said track elements being
operated by suitable track circuits in a man-
ner to put them in their danger condition
when the block which they protect is unoc-
cupied and the next block in advance is oc-
cupied, and to put them in their clear traffic
condition when both of said blocks are oc-
cupied.

9. In a train control system of the type
in which control influences are transmitted
electro-magnetically through an intervening
air gap, car-carried apparatus including in-

fluence receiving means, and brake control
apparatus governed thereby; and trackway
means comprising track elements for trans-
mitting control influences to said influence
receiving means, said track elements being
operated by suitable track circuits in a man-
ner to put them in their danger condition
when the block in which they project is un-
occupied and the next block in advance is
occupied, and to put them in their clear
traffic condition when both of said blocks
are occupied, said track elements being
placed a distance in advance of the begin-
ning of the track circuit so that a train en-
tering a block when the next block in ad-
vance is occupied at a predetermined low
maximum speed, will not encounter the
track elements until they have assumed their
clear condition due to the entrance of said
train in said block.

10. In a train control system adapted for
block signaled and interlocked territory, the
combination of a car-carried means includ-
ing a magnetic core having a winding there-
on, means for magnetizing said core, elec-
tro-responsive means for controlling the
train governed by said winding; and a track-
way means for block signaled territory effec-
tive in transmitting control influences when
a train is traveling at speeds above a pre-
dicted low maximum speed, and another
trackway means for interlocked territory
effective in transmitting control influences at
very low speed or when said car-carried
means stands directly over said another
trackway means.

11. In an automatic train control system,
the combination with means on a railway ve-
hicle inductively responsive to alternating
current flowing in a trackway circuit for
automatically applying the brakes on a ve-
hicle dependent upon the flow of such cur-
rent, and trackway apparatus for conflict-
ing routes of trackway comprising a circuit
for each of said routes and a source of al-
ternating current therefor, and manually
operable interlocked electrical switching
means for controlling the flow of alternating
current in said circuits.

12. In an automatic train control system,
the combination with means on a railway
vehicle inductively responsive to alternating
current flowing in a trackway circuit for au-
tomatically applying the brakes on a vehicle
in accordance with the flow of such current,
and trackway apparatus for two conflicting
sections of trackway comprising a circuit
and a source of alternating current associat-
ed with each of said trackway sections, man-
ually operable means for controlling the flow
of alternating current in said circuits, and
means controlled in accordance with the flow
of current in the conflicting trackway cir-
cuit for preventing said manually operable
means from being effective.

13. In an automatic train control system, the combination with means on a railway vehicle responsive to alternating current flowing in a trackway circuit for automatically applying the brakes on a vehicle in accordance with the flow of such current, and trackway apparatus for two conflicting sections of trackway comprising a circuit and a source of alternating current associated with each of said trackway sections, and manually operable means dependent for its effective operation on traffic conditions ahead of the section in question for controlling the flow of current in each of said circuits.
14. In an automatic train control system, the combination of car-carried apparatus including a car element having an exciting coil, an influence receiving coil, and an electro-responsive device of the stick type controlled by said receiving coil, and of trackway apparatus adapted to cooperate with said car element comprising a track element of magnetic material, a coil on said track element, and means for closing said coil in a closed circuit of low resistance under clear traffic conditions and for energizing said coil by alternating current under danger traffic conditions.
15. In an automatic train control system, the combination of car-carried apparatus including a car element having an exciting coil, an influence receiving coil, an electro-responsive brake controlling device of the stick type controlled by said receiving coil, and manually operable means for restoring said device to normal only after operation thereof, a trackway element comprising a core, a winding on said core closed in a circuit of low resistance under clear traffic conditions, and a source of alternating current adapted to deenergize said electro-responsive device by inducing a voltage in said receiving coil when said car element passes over a trackway element in its effective stopping condition.
16. In an automatic train control system, the combination with car-carried apparatus comprising a car-carried core of magnetic material, a normally excited primary winding on said core, an influence receiving winding on said core, and trackway equipment for effecting automatic control of said car-carried apparatus when the car travels at an excessive speed under danger traffic conditions ahead, said trackway equipment including a trackway element adapted to transmit a control influence to said influence receiving coil, and control means for putting said trackway element in its active stopping condition under danger traffic conditions ahead and for putting it in its clear non-stopping condition a predetermined time after a train passes a point a predetermined distance in the rear of said element.
17. Car-carried apparatus for automatic train control systems comprising, a core of magnetic material, a primary winding and a secondary winding on said core, a source of direct current for energizing said primary winding, another source of direct current for energizing a relay connected in series with said secondary winding, and means for automatically varying the current flow through said relay in accordance with voltage changes of said first mentioned source.
18. In an automatic train control system, the combination with car-carried apparatus comprising a control relay energized by a circuit including a front contact of said relay, a brake control device acting on the usual air brake system controlled by said relay, means for shunting the front contact of said control relay only if the brakes are applied to a predetermined extent, and trackway equipment including a trackway element adapted to transmit a control influence to momentarily deenergize said control relay when in its active stopping condition, and control means for putting said trackway element in its active stopping condition under danger traffic conditions ahead and for putting it in its clear non-stopping condition a predetermined time after a train passes a point a predetermined distance in the rear of said element.
19. In an automatic train control system, the combination with a railway vehicle, car elements on opposite sides of the vehicle each having a primary and a secondary coil surrounding a core of magnetic material, a circuit including a source of energy, said primary coils and a train control device, a relay, a circuit including said relay and said secondary coils, and trackway elements located along the trackway in position to simultaneously cooperate with said car elements and change the magnetic reluctance of its corresponding core as the vehicle passes by said trackway elements.
20. A train control system comprising, a brake control device on a railway vehicle, a control relay energized by a circuit including a front contact of said relay for controlling said brake control device, apparatus partly on the vehicle and partly along the trackway for momentarily deenergizing said relay under predetermined traffic conditions ahead, and means effective if the pressure in the brake pipe of the vehicle is reduced to a certain value for shunting the contact of said relay.
21. A train control system comprising, a brake control device on a railway vehicle, a control relay energized by a circuit including a front contact of said relay for controlling said train control device, apparatus partly on the vehicle and partly along the trackway for momentarily deenergizing said relay under predetermined traffic conditions ahead, and means including a manually op-

erable device for restoring said brake control device to normal after an automatic actuation thereof, said last mentioned means being effective only if the brake pipe pressure has been reduced to a predetermined extent.

22. A train control system comprising means for applying the brakes of a railway vehicle automatically including a relay energized by a circuit including front contact 10 of said relay, and means for shunting said front contact only if the brakes of the vehicle have been applied to a predetermined extent.

23. Car-carried apparatus for automatic train control systems comprising, a car-carried core of magnetic material, a primary winding and an influence receiving winding on said core, a source of direct current for energizing said primary winding, another source of direct current for energizing a 20 relay connected in series with said influence receiving coil, and automatic means included in a common portion of said two circuits for varying the current in said relay in accordance with the variation of current in said 25 primary winding.

24. An automatic train control system comprising, car-carried apparatus including a core of magnetic material having a primary and a secondary winding thereon, a direct current source of energy for energizing said primary winding, a brake control device actuated upon the reception of a control influence by said secondary winding, and trackway equipment magnetically cooperating with said core for transmitting control influences to said secondary winding, said trackway equipment including a track device comprising an inert body of iron when in its active stopping condition, and 40 another track device energized at times by alternating current.

25. In trackway apparatus for an automatic train control system for governing trains over conflicting routes at interlocking 45 plants, the combination with two tracks of conflicting routes, a circuit associated with each of said tracks and adapted to transmit control influences inductively through an intervening air gap to suitable train carried 50 train control apparatus, said circuits being interlocked so that only one of said circuits may be in the clear traffic condition at one time.

26. In trackway apparatus for automatically governing train movements over conflicting routes at interlocking plants, the combination with two tracks having conflicting portions, a circuit associated with

each of said tracks and adapted to transmit control influences inductively to suitable 60 train carried train control apparatus, and manually operable means for energizing said circuits, said manually operable means being ineffective to put one of said circuits in its clear traffic condition while the other circuit 65 is in its clear traffic condition or while the conflicting track portion is occupied.

27. In an automatic train control system; the combination of car-carried apparatus including a control relay having a front contact; a secondary influence receiving coil; a secondary circuit including the winding and front contact of said relay, said secondary coil and a source of energy in series; means governed by said relay for bringing the train 70 to a stop when said relay assumes its retracted position; and of trackway means including a trackway device for inducing a voltage in said secondary coil upon passage of said coil by said trackway device when in 75 its active condition; and means for rendering said trackway device inactive a predetermined time after an approaching train passes a point a predetermined distance in the rear of said trackway device; whereby 80 the train is only stopped if it travels above a predetermined speed when approaching said trackway device.

28. In an automatic train control system; the combination of a car-carried apparatus 90 including a control relay having a front contact; a car element comprising a core of magnetic material having a primary and a secondary winding thereon; means for energizing said primary winding; a secondary 95 circuit including the winding and front contact of said relay, said secondary winding and a source of energy in series; brake control means governed by said relay; and of trackway means including a trackway device for inducing a voltage in said secondary winding by flux emitted by said primary winding upon passage of said car element by said trackway device when in its active condition; and means for rendering said trackway device inactive a predetermined time after an approaching train 100 passes a point a predetermined distance in the rear of said trackway device; whereby 105 the brake control means is operated if the train travels above a predetermined speed when approaching said trackway device.

In testimony whereof I affix my signature.

CHARLES S. BUSHNELL.
